CEILING CONSTRUCTION

Alexander F. Styne, 3810 Anderson Road, Coral Gables, Fla., and Lee James, 915 W. 60th St., Hialeah, Fla.
Filed May 21, 1963, Ser. No. 281,975
8 Claims. (Cl. 98—40)

This invention relates to ceiling constructions and particularly of a ceiling of the suspended or hung type.

The invention further relates to an additional and highly desirable use of various kinds of suspended ceilings for the diffusion or distribution of mechanically conditioned air.

Suspended (or "hung") ceilings, both of light-transmitting or opaque materials have gained wide uses in residential, commercial and industrial structures. As air conditioning is fast becoming a marketing requirement for all types of new or converted structures, the supply of high-level illumination and mechanically conditioned air requires new solutions.

Many advantages can be gained by providing this dual function to suspended ceiling structures. For example, the mechanically conditioned air can be supplied from the duct endings or openings into the space above the suspended ceiling without expensive diffusers. In commercial and industrial buildings which are designed to anticipate changes in the use of space, air ducts can be changed or openings relocated without the need for any finishing or enclosing work. As the space above the suspended ceiling will become a plenum with higher air pressure than the occupied space below it, a constant air movement across the ceiling panels will prevent dust settling on either upper or lower surfaces and so alleviate maintenance chores. For the conversion of older structures where air conditioning systems are installed to update their usefulness, installation costs could be materially reduced. Further, the distribution of apertures throughout an entire room or space will reduce the draft effect encountered at times with conventional diffusers.

In systems currently in use the metal members of such suspended ceilings are only designed to hold in place and to support modular panels of various plastic or fibre materials. By virtue of this invention such supporting members are given the additional function of diffusing mechanically conditioned air to the occupied space below a suspended ceiling. It is therefore the object of this invention to create a structural system that incorporates the mechanical function to distribute conditioned air in an overall even pattern to the occupied space below the suspended ceiling. It is yet another object of this invention to create a structural type of member which permits the use of lightweight material with a smaller bending factor than was heretofore accomplished and so reduce the number of points where hangers must fasten this system to the structural ceiling or joists of the building. A further object of this invention is to create an assembly method which virtually avoids the use of tools under normal conditions and is foolproof to the point that it can be assembled by untrained persons.

In the drawings:

FIGURE 1 is an exploded perspective view of a ceiling structure in accordance with the invention.

FIGURE 2 is a perspective view of one corner section of a suspended ceiling with the parts in assembled relation,

FIGURE 3 is a perspective view showing wall attaching means for channel members,

FIGURE 4 is a similar perspective view showing a slightly modified use of the device,

FIGURE 5 is a fragmentary side elevation showing a modified form of wall attaching means,

2

FIGURE 6 is a section taken substantially on line 6—6 of FIGURE 5,

FIGURE 7 is a perspective view showing the wall attaching means of FIGURE 5, and

5 FIGURE 8 is a transverse sectional view illustrating a modified form of the invention wherein a baffle plate is disposed below the channels.

Referring specifically to the drawings, there has been provided a plurality of head beams 5. The head beams 10 are relatively thin sheet metal of inverted channel form in cross section. Each of the beams embodies spaced apart side walls 6, forming a channel 7 and with the walls 6 terminating in right angle flanges 8.

The apex of the beams 5 are formed flat, as indicated 15 at 9. Each of the side walls 6 are provided with a plurality of equidistantly spaced apart slots 10, for a purpose to be presently described.

The several beams 5 are cut to predetermined lengths 20 for spanning a particular ceiling area of a building and to form a frame of predetermined dimensions. In order to form a relatively rigid frame, there has been provided right angle corner members 11, of generally U-shape and with the vertical legs of the U, indicated at 12 teleoscopically engaged into the channel 7 of the adjacent beams. 25 The legs 12 are provided with bosses 13 that have a snapping engagement into adjacent slots 10, see particularly FIGURE 2. The corner members 11 are also provided with flanges 14 that underlie the flange 8 of the beams at assembly. Cross beams 15 constructed similar 30 to the beams 5 are adapted to have interfitting engagement with the beams 5 at assembly. For this purpose, the beams 5 have been notched at 16 and the beams 15 have been notched at 17 so that the beams have interfitting engagement and with the tops of the beams 15 being 35 flush with the tops of the beams 5. At the points of intersection, the flanges 8 of the beams 5 have been pressed downwardly, as indicated at 18 to receive the flanges of the beams 15 and whereby the beams are in mating engagement in much the manner of an egg crate. The 40 beams 15 may be provided with extension 19 having an end portion notched at 20 to engage the notch 16 of the outermost beams 5.

In assembled relation, as illustrated in FIGURE 2 the structure is elevated and supported from the rafters or other ceiling structure of the building by suspension wires 45 21 and whereby the structure may be supported at a predetermined spacing below the permanent ceiling of the building such forming a substantial air space between the permanent structure and the suspended ceiling. The wires 21 are connected through any particular slot 10 as will be obvious.

50 Since it is desirable that the suspended ceiling of this invention constitute illuminating and air diffusing means, panels, either opaque or translucent will be inserted upwardly and have resting engagement upon the flanges 8. Suitable illuminating means will be installed upon the rafters or other permanent ceiling of the building when the panels are translucent and in any desirable manner, conditioned air may be directed into the space between the permanent ceiling and the suspended ceiling and with the air being pressurized so that it will flow through the slots 55 10 to be ejected downwardly from the channels 7. The panels are indicated in FIGURE 2 at 22.

60 In the use of this form of the invention, several parallel beams 5 are arranged in spaced apart relation with their corners connected by their corner members 11. The cross beams 15 are then disposed between the notches 16, forming a substantially grid structure that may be subsequently elevated to span the ceiling of the building or, the several panels may be subsequently assembled at their point of use. The beams are then supported by the wires 65 21 in the usual manner. The corner members 11 having

fitment into the channels of the beams 5 have automatic locking by the bosses 13, forming a very rigid structure. The several beams 5 and 15 being of relatively light gauge material are preferably formed upon a suitable bending machine and the beams due to their construction become very rigid with little, if any, tendency to flex. The structure so formed extends from wall to wall of the building and may be either suspended by the wires 21 or the ends of the beams may be anchored into the walls in a manner that will be presently described. The panels 22 perform various functions, such as light diffusion, sound absorption, thermal insulation or simply as closures forming the ceiling. Further operation of the device will follow.

The extension members 19 will be formed in various lengths so that they can also be used as joining elements where the ceiling or room dimensions exceeds the greatest lengths of the beams 5 or 15. The engagement of the beams 15 into the notches 16 or the engagement of the extensions 19 into the notches 16 have a snug force fit engagement that will prevent the movement of the beams with respect to each other. The corner members 11 thus provide a perimeter support and closing members for wall to wall installation.

In FIGURES 3 and 4, there has been illustrated a wall anchor for certain of the beams and whereby to anchor the beams at predetermined points along the walls. The anchoring device or wall hanger is installed in one corner and at right angles to the beams 5 or 15. This wall hanger is formed to accommodate both the regular beams 5 or 15 and the extensions 19, if this should be necessary. The wall hanger can be installed with a conventional fastening device. The wall hanger is stamped from a sheet metal plate having wing sections 23, apertures 24 for the passage of fastening devices and the wings carry the forwardly projecting stud that is proportioned to have fitment into the open ends of the beams 5 or 15 and also the extensions 19. The stud and its supporting plates 23 are stamped from a suitable sheet metal and the stud has a relatively wide portion 25 and a narrower portion 26 all being integral with the plate 23. The narrow portion 26 has fitment into the open ends of the extensions 19 while the portion 25 has fitment into the open ends of the beams 5 or 15. The wall hanger may be initially engaged with the beams 5 or the extensions 19 and then elevated for securement to the wall area by the driving of suitable nails or other wall fastenings through either of the apertures 24. FIGURE 3 illustrates the extension 19 engaging the stud portion 26 while FIGURE 4 illustrates the beams 5 or 15 engaged over the stud portion 25.

In FIGURES 5-7, there has been illustrated a modified form of wall hanger. This hanger consists of two bifurcated metal plates 27 and 28 that are provided with notches 29 in their marginal portions whereby to engage the side walls of the beams 5 or 15. The plates 27 and 28, as clearly shown in FIGURES 5 and 6 have fitment within a selected slot 10. The two plates are held apart under tension by a compression spring 30 that is fitted over the innermost forked part of each plate. Into the forks of each plate, indicated at 31 and passing through the center of the compression spring is a double-headed, case-hardened nail 32. The nail 32 has a driving head 33 and a spaced shoulder 34. The plate 27 may be held against movement by clinching the side wall of the slot 10, as shown in FIGURE 5 at 35. The plate 28 is thus free to slide longitudinally of the slot 10 when a driving tool is applied to a head 33. The nail 32 is provided with a sharpened point 36 that may be driven into a wall area or the nail may be driven into a previously installed wall anchor 37 of conventional construction.

In the use of this wall anchor, the device including the plates 27 and 28 in assembled relation as shown in FIGURE 7 is inserted through a selected slot 10 and with the forward end of the nail projecting beyond the end of the beam 5 then, by employing a suitable driving tool that is inserted upwardly through the channel 7, the nail 32

is driven into the wall or wall anchor, forming a very desirable and effective anchoring means for the ceiling members.

Since the suspended ceiling has a multiple purpose, being to provide light diffusion, sound absorption, thermal insulation or simply as closures formed by the panels 22 and to also diffuse mechanically conditioned air from above the suspended ceiling construction into the occupied space below, such air passing through the slots 10 and then downwardly from the channels 7, it may be found desirable that rather than to have the air forced straight downwardly, that means be provided to diffuse the air in a horizontal or lateral path and for this purpose, there has been provided a baffle plate 38 having spring clips 39 that extend upwardly into the channels 7 for snapping engagement into the slots 10. The baffle plate 38 is located a predetermined distance below the channel and below the flanges 8 and functions to diffuse the air laterally rather than downwardly.

In use, the ceiling being assembled and supported by either the wires 21 or the wall hangers, and with the panels being disposed upon the flanges 8, air by any suitable pump preferably conditioned air is forced into the space between the permanent ceiling and the suspended ceiling and circulates through the space to flow through the slots 10 for discharge from the channels 7. As before stated, the panels may be translucent or even transparent and suitable lighting fixtures suspended from the rafters or other permanent ceiling. In certain instances, it may be desirable to reverse the flow of air, such as for the ventilating purposes and in such case, the air from the room area is exhausted upwardly through the channel 7 and through the slots 10 for discharge in any well known manner.

It will be apparent from the foregoing that a very novel form of suspended ceiling has been provided. The several elements are economically formed, easily installed and provide a suspended ceiling having all of the characteristics of light diffusion and conditioned air diffusion. Suspended ceilings heretofore employed are usually formed of relatively heavy metal and in most instances extruded metal and are relatively heavy and difficult to assemble and install while the device of this invention provides inverted U-shaped beams that may be economically formed from shaped sheet metal upon a suitable bending machine and due to its channel formation is extremely strong.

It is to be understood that the invention is not limited to the precise construction shown, but that changes are contemplated as readily fall within the spirit of the invention as shall be determined by the scope of the subjoined claims.

We claim:

1. A suspended drop ceiling to be supported by rafters or other permanent ceiling structure of the building, the ceiling adapted to be suspended in spaced relation to the permanent ceiling to provide an upper air space, the suspended ceiling being formed of spaced apart inverted U-shaped beams and a plurality of spaced apart cross beams of inverted U-shape, the first named beams and the cross beams having notched interlocking engagement at their point of crossing, whereby the cross beams extend continuously across the first-mentioned beams each of the beams being shaped from sheet metal, each of the beams having a downwardly opening channel and with the sides of the beams provided with a plurality of spaced apart slots that communicate with the air space and with the channels, whereby mechanically conditioned air pumped into the upper space will flow through the slots and the channels for discharge into an occupied space below the ceiling, the side walls of the beams having right angle flanges for the resting support of closure panels and means to support the suspended ceiling from either the rafters or the side walls.

2. A drop or suspended ceiling for installation in spaced relation to rafters or other permanent ceiling of a

building and whereby to create an upper air space, the drop ceiling extending from wall to wall, the drop ceiling consisting of a plurality of inverted U-shaped beams of sheet metal and with certain of the beams arranged at a right angle and crossing other beams and in notched engagement therewith to form substantially a grid, the beams embodying a U-shape head having spaced apart side walls and with the side walls terminating in outwardly extending right angle flanges, the head providing a downwardly opening channel, each of the side walls being provided with spaced apart slots, each of the beams being open at their ends, extensions fittingly engaged in the open ends of the beams whereby the beams may conform to room areas, L-shaped corner connectors fittingly engaged in certain of the beams to form a perimeter beam, means to suspend the drop ceiling from the rafters or permanent ceiling, the upper air space being further formed by panels that rest upon the flanges, the upper air space adapted to receive mechanically conditioned air that is pressurized to flow through the slots for discharge downwardly from the channels to an occupied area below the drop ceiling.

3. The structure according to claim 2, wherein the extensions are of inverted U-shape and with the extensions having a telescopic engagement into the open ends of the beams, the extensions upon their opposite sides being provided with bosses that have snapping engagement into the slots and whereby the extensions are effectively retained in their telescopic engagement.

4. The structure according to claim 2, wherein the first-named beams and the cross beams are notched to have the interlocking engagement and with the flanges of the first-named beams being distorted to receive the flanges of the cross beams so that the several beams will be flush with each other.

5. The structure according to claim 2, wherein the corner connectors are of inverted U-shape and adapted to telescopically engage within the channels of adjacent perimeter beams, the corner connectors having right angle flanges corresponding to the flanges of the beams and at assembly underlying the flanges of the beams, the connectors being provided upon their side walls with bosses that engage into the slots of the beams to maintain the connectors against shifting with respect to the beams.

6. A drop ceiling for use in a lower spaced relation to ceiling rafters or other permanent ceiling of a building that comprises a plurality of inverted U-shape beams of the type wherein the beams have spaced side walls forming a downwardly opening channel and with the side walls terminating in right angle flanges, the ends of the channels being open, the side walls of the channels having a plurality of spaced apart slots, certain of the beams being in crossed relation to form an open grid, certain of the beams being anchored at their ends to adjacent side walls of a building, the anchoring means having a plate having a forwardly projecting lug telescopically engaging the open ends of the beams to be anchored to the side walls, said plate being adapted to be fastened to a wall, said leg having parts of different size, certain of the beams having

5

6

U-shape extensions that have telescopic engagement with the beams and with parts of the lugs of one size, and the parts of the lugs of another size being engageable by the ends of the beams, the plate means and the lug being formed integral from sheet metal.

7. A drop ceiling for use in a lower spaced relation to ceiling rafters or other permanent ceiling of a building that comprises a plurality of inverted U-shaped beams, the beams being formed of sheet metal and having spaced side walls forming a downwardly opening channel for the full length of the beam and with the side walls terminating in right angle flanges for the resting support of panels, the ends of the channels being open, the said side walls of the beams having a plurality of spaced apart slots, certain of the beams being in crossed relation to form an open grid that is closed by the panels, certain of the beams being notched to engage notches in the beams that cross them, certain of the channels being anchored at their ends to adjacent side walls of the building, the anchoring means being an elongated cylindrical bar that is disposed in the channels of the beams and with the bar projecting beyond the beams and having a sharpened end, the bar being supported by a pair of bifurcated plates that are disposed within the channel and with portions of the plates engaging one of the slots, means for fixing one of the plates relative to the slot, the bar having a head portion and a spaced apart collar that is engaged with respect to the bifurcations, one plate being yieldable and biased in one direction by a coil spring around the bar, the said bar adapted to be driven into a wall area by impact engagement with a tool that is disposed into the channel against the head of the bar and whereby the bar may be driven into a wall area for fixed attachment of the drop ceiling, beams being in crossed relation with respect to the other beams and with the second named beams being notched to engage notches in the other beams and whereby to form an open grid, the said ceiling providing an air space thereabove that receives mechanically conditioned air that is adapted to flow through the slots and downwardly to the occupied area below the ceiling.

8. The structure according to claim 7 wherein the downwardly opening channels are provided with spaced apart baffle plates whereby to direct the mechanically conditioned air outwardly from the channels and in a lateral direction and spring clips carried by the baffle plate that extend upwardly into the channels for clipping engagement into the slots of the beams, the said plates being disposed in spaced apart relation below the beams.
